UNITED STATES PATENT OFFICE.

JOHN BECKER, OF HYDEPARK, MASSACHUSETTS, ASSIGNOR TO BECKER-BRAINARD MILLING MACHINE COMPANY, OF PORTLAND, MAINE, A CORPORATION OF MAINE.

DESIGN FOR AN UPRIGHT FOR HORIZONTAL MILLING-MACHINES.

SPECIFICATION forming part of Design No. 35,449, dated December 17, 1901.

Application filed November 14, 1901. Serial No. 82,320. Term of patent 14 years.

To all whom it may concern:

Be it known that I, JOHN BECKER, a citizen of the United States, residing at Hydepark, in the county of Norfolk and State of Massachusetts, have invented and produced a certain new and original Design for the Uprights of Horizontal Milling-Machines; and I do hereby declare the following to be a full, clear, and exact description of the invention, such as will enable others skilled in the art to which it appertains to make and use the same.

Referring to the drawings, Figure 1 is a view in front elevation, Fig. 2 is a view in side elevation, and Fig. 3 is a perspective view, illustrating my design for the upright of a milling-machine.

As shown in the drawings, the leading and material features of my design are described as follows: The base is rectangularly parallelepipedal in general form, provided with downwardly-projected portions, the adjacent surfaces of which are planar and converging. A web rises from the upper surface of the base, the margins of which converge on con-

cave-curved lines near the base and thereafter extend upwardly on lines slightly converging as the distance from the base increases. The web is provided with a vertical central elongated parallel-sided semicircularly-ended opening and with lateral relatively narrow vertical openings on each side of the said central opening, said lateral openings being surrounded by plane surfaces raised above the level of the surface of the web.

Having thus described my invention, I claim as new and desire to secure by Letters Patent—

The design for the upright of a horizontal milling-machine, substantially as shown and described.

In testimony whereof I affix my signature in presence of two witnesses.

JOHN BECKER.
